US00D712345S

(12) **United States Design Patent**
Kwon et al.

(10) **Patent No.:** **US D712,345 S**
(45) **Date of Patent:** **** Sep. 2, 2014**

(54) **BATTERY FOR PORTABLE TERMINAL**

(71) Applicant: **LG Chem, Ltd.**, Seoul (KR)

(72) Inventors: **Sung-Jin Kwon**, Daejeon (KR);
Ki-Woong Kim, Daejeon (KR);
Dong-Myung Kim, Daejeon (KR)

(73) Assignee: **LG Chem, Ltd.** (KR)

(**) Term: **14 Years**

(21) Appl. No.: **29/466,065**

(22) Filed: **Sep. 4, 2013**

(30) **Foreign Application Priority Data**

Mar. 8, 2013 (KR) 30-2013-0011977

(51) **LOC (10) Cl.** **13-02**

(52) **U.S. Cl.**

USPC **D13/103**

(58) **Field of Classification Search**

USPC D13/102–104, 110, 118–121, 184, 199;
429/94, 96–100, 152–153, 162–163,
429/176

See application file for complete search history.

(57) **CLAIM**

The ornamental design for a battery for portable terminal, as shown and described.

DESCRIPTION

FIG. 1 is a front perspective view of a battery for portable terminal according to our design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

1 Claim, 4 Drawing Sheets
